UNITED STATES PATENT OFFICE.

CLARENCE H. RIEGEL, OF NILES, OHIO.

METHOD OF BILGING A CYLINDRICAL BODY OF SHEET METAL.

Application filed August 5, 1921. Serial No. 490,153.

To all whom it may concern:

Be it known that I, CLARENCE H. RIEGEL, a citizen of the United States, residing at 434 Robbins Ave., Niles, in the county of 5 Trumbull, State of Ohio, have invented certain new and useful Improvements in Methods of Bilging a Cylindrical Body of Sheet Metal, of which the following is a specification.

10 This invention relates to the art of making metal casks or barrels, and consists of an improved method of bilging cylindrical bodies of sheet metal and co-incidently forming an annular channel and bead in the bilged area. Thus the steps taken are intended to bilge the body, and also to strengthen the body against lateral pressures at its largest diameter where the wall is reduced in thickness by bilging, and to 20 produce a spring fold in the material itself adapted to absorb such shocks as result in dropping the barrel body on either of its chimes or ends.

In the annexed drawings, Fig. 1 is a diagrammatic view of a set of expanding dies and Fig. 2 is a vertical section of a machine embodying such dies, each figure showing a straight cylinder sleeved over the dies preparatory to bilging operations. Figs. 3 and 25 4 are corresponding views to Figs. 1 and 2, showing the dies expanded and one-half of the cylinder bilged. Fig. 5 is a diagrammatic view showing the partly bilged cylinder sleeved in an inverted position over the collapsed dies, and Fig. 6 is a view corresponding to Fig. 5 excepting that the dies are expanded and the cylinder is shown as bilged at each side of an annular channel and bead formed in the middle of the cylinder. Fig. 7 is an enlarged section and side elevation of the product of the method 30 involved herein.

To illustrate the steps taken in producing a bilged barrel I show in Figs. 2 and 4 a machine or apparatus in which a series of 45 segmental dies 5 are placed in a circle radially opposite a reciprocable thrust rod 6 which is actuated by an eccentric or crank shaft 7 and an eccentric strap 8. A base 50 plate 9 supports standards 10 in which shaft 7 has rotatable bearing, and the dies 5 are secured to vertical members 11 which are supported to slide upon a table 12 resting upon the upper ends of standards 10. The 55 die carrying members 11 are actuated by toggle links 14 which connect with an adjustable

sleeve or collar 15 on reciprocable rod 6 and when the rod moves downwardly the dies are spread apart until the links are horizontal. Each die is curved transversely on a larger radius than the radius of the cylindrical shell when it is first sleeved over the dies, and the longitudinal curvature of the die is less than half the length of the cylinder or shell to be operated upon. As 60 shown each die tapers downwardly from a rounded shoulder 16 located at or relatively near the transverse median line of the cylinder when at rest opposite the dies as shown in Fig. 2, and the first step involved 65 in actually bilging the cylinder occurs when the dies are forced outwardly by a one-half revolution of the eccentric which draws the thrust rod downwardly until the operating parts are in the position shown in Figs. 70 3 and 4. Thus the first step in bilging the cylinder consists in expanding one end portion thereof to a larger diameter on tapering lines longitudinally while coincidentally forming an annular shoulder or offset 75 17 approximately midlength of the cylinder. In so doing the metal wall of the cylinder is reduced in thickness gradually from the bottom end of the cylinder to the annular shoulder or offset 17 but the base or bottom of the offset is not appreciably decreased in thickness inasmuch as the upper half and the middle part of the cylinder is not expanded in this operation.

The upper half of the cylinder is expanded and bilged in exactly the same way as the lower half, which step follows as soon as the dies have been collapsed by the continuing rotation of the eccentric to the place of beginning to permit the partially expanded cylinder to be removed from the dies and then inverted and again sleeved over the dies to bring the plain straight portion thereof opposite the tapered curved portion of the dies as collapsed and shown in diagram in Fig. 5. The eccentric is then rotated a second time to spread the dies uniformly to their limit, thereby expanding and stretching the straight wall of the cylinder to the same bilge and contour as the end 100 105 first operated upon while producing at the same time a second annular offset 17' which together with offset 17 forms a round annular channel and internal bead 18 midway between the two bilged portions, see Fig. 110 6. The bilged product is then removed from the dies as soon as the eccentric completes

2
its cycle of movement to collapse the die, and heads of any suitable kind may then be affixed in any suitable way to the opposite ends of the bilged cylinder to make a complete cask or barrel.

The middle belt or bead 18 is shown in the drawings as rounded and as involving only a small portion of the cylinder, but a wider belt may be formed in the same way, 10 and as this bead or belt portion is not materially expanded by the dies it remains substantially unaltered in thickness and strength and provides a substantial reenforcement for the bilged body where otherwise stretched to its greatest extent. The dies in moving outwardly engage the cylinder first near its middle and then on circular lines moving toward one end, and at the beginning only the meeting corners of 15 the dies at their largest diameter engage the circular wall of the cylinder. During the final stages of bilging each half of the cylinder, the dies move outwardly at gradually decreasing speed and increasing power 20 on account of the eccentric and crank movement involved and because the links move on an arc toward a horizontal line which brings the pivots of the links on a dead center. 25

30 What I claim is:

1. A method of making a cask or barrel of sheet metal, consisting in expanding portions of the respective end halves of a sheet metal cylinder to substantially the same diameter by applying an outwardly-moving pressure uniformly at equi-distant radial points, beginning first within one end half of the cylinder to completion and then separately within the opposite end half of said 35 cylinder. 40

2. A method of making a metal cask or barrel consisting in expanding and stretching an annular enlargement in one end portion of a sheet metal cylinder by applying pressure internally at uniformly-spaced 45 radial points within said end, and then repeating said step in the opposite end portion of said cylinder, and leaving an unex-

panded portion intermediate said enlargements. 50

3. A method of making a cask or barrel of sheet metal, consisting in expanding the opposite end halves of a cylindrical body to substantially the same shape and diameter separately and successively by localizing the application of equal pressure at equi-distant radial places internally of said cylinder, first in one end of the cylinder and subsequently in the opposite end. 55

4. A method of making a cask or barrel, 60 consisting in expanding a cylindrical sheet-metal body on reversely-tapering lines, beginning at the middle of said body and localizing an expanding pressure first within one end without altering the opposite end 65 and then subsequently within the opposite unaltered end of said body.

5. A method of bilging a cylindrical body of sheet metal, consisting in expanding separate portions of the body successively on 70 opposite sides of the transverse medial line of the body and forming an annular belt intermediate said expanded portions.

6. A method of bilging a cylindrical body of sheet metal, consisting in bilging one- 75 half of the body while forming an annular offset approximately near the middle thereof, and repeating said operation in the other half of the body.

7. A method of bilging a cylindrical body of sheet metal, consisting in stretching the body to a larger diameter near its middle than at its ends in one end section of the body; in repeating said step in the opposite end section; and in forming an annular 85 channel and belt in the middle section of the body.

8. A method of bilging a cylindrical body of sheet metal, consisting in expanding one end portion of the body to a larger diameter 90 on tapering lines longitudinally, while coincidentally forming an annular offset approximately midlength of the cylinder; and then repeating the same operation in the opposite end portion of the body.

CLARENCE H. RIEGEL.
